Attorney

UNITED STATES PATENT OFFICE.

JOSEPH R. WALLACE, OF SAN ANGELO, TEXAS, ASSIGNOR OF ONE-HALF TO JAMES F. PRICE, OF SAN ANGELO, TEXAS.

AUTOMATIC GATE.

Application filed November 3, 1923. Serial No. 672,536.

To all whom it may concern:

Be it known that I, JOSEPH R. WALLACE, a citizen of the United States, residing at San Angelo, in the county of Tom Green 5 and State of Texas, have invented certain new and useful Improvements in Automatic Gates, of which the following is a specification.

The present invention consists of an automatic gate for use in practically any capacity in which a gate now serves, in addition to which the structure of the present invention is such as to permit use of the same as a door for garages or the like.

An object of the invention is to provide 15 a device of this character which is simple in construction yet durable to permit the gate to be swung on its axis by the impingement of an object therewith without mutilating or otherwise damaging either the gate 20 or the object.

Other objects of the invention will be apparent from the following description of the present preferred form of the invention 25 taken in connection with the accompanying drawings wherein:—

Fig. 1 is an elevational view of a gate constructed in accordance with this invention illustrating its application;

Fig. 2 is a vertical sectional view of the same; and

Fig. 3 is an elevational view of a slightly modified form of gate.

In the form of invention shown in Fig. 35 1 of the drawings, a portion of a fence 4 is illustrated in order to show the relative position of the gate thereto. By preference, a base supporting frame 5 is countersunk in the earth transversely between the fence 40 posts.

The form of gate shown in Fig. 1 consists of a substantially rectangular structure 6 preferably formed from pipes the ends of which are screwthreaded as indicated at 7 for engagement in complementary threads formed in elbows 8. A reticulate structure such as indicated at 9 may be mounted in the frame 6 although if desired this may be modified or completely omitted depending upon the use which the gate is intended to serve. The frame is equipped on one side with a pair of strips 10 made of wood, metal 45 or other suitable material, one strip being

mounted adjacent each end of the gate and secured to the frame. The strips extend transversely across the frame and are positioned so as to lie beyond the base 5 so that when the gate is in a horizontal position these strips will serve as runways or traction strips for a vehicle moving over the 55 gate. The lower portion of the gate frame is movably mounted between loop straps 11 carried by the upper marginal edges of the base 5. The gate is normally held in a vertical position by means 12 which in the present instance consists of a helical spring mounted on each side of the gate one end thereof being secured to the lower end of the gate, as indicated at 13, while the opposite end is engaged with a chain 14 secured to the base 5.

It is apparent that when an object, such for instance as a motor vehicle impinges the gate that the latter will move downwardly against the resistance of the springs 12 permitting the vehicle to ride over the strips 10. As soon as the vehicle crosses the gate, the latter will move upwardly into a vertical plane by the action of the springs 12.

In the form of invention shown in Fig. 80 3 of the drawings, a base frame 5' is provided which is relatively longer than the frame 5 and is also countersunk in the earth. The gate shown in Fig. 3 consists of a frame formed from a single strand of wire 6' which may be bent into rectangular shape 85 and has one end thereof formed to provide an eye 15 through which the opposite end of the strand extends to provide a shank 16. This shank is adapted to depend in the base frame 5' and has its lower end formed to 90 provide an eye 17 which carries a weight 18. The gate frame is pivotally mounted on the base 5' beneath loop straps 11'. Runways or treads 10' may be secured to one side of the gate frame for use in the same 95 manner as the runways 10 shown in Fig. 1.

In use of the form of invention shown in Fig. 3 it is apparent that impingement of an object with the gate will urge the latter into a horizontal position thereby elevating the weight 18. As soon as pressure is released from the gate the weight 18 gravitates thereby returning the gate to a vertical position.

It is of course to be understood that 105

various changes may be made in the device of this invention especially in the details of construction, proportion and arrangement of parts within the scope of the claims here-
5 to appended.

What is claimed is:—

An automatic gate including a movably

mounted gate frame composed of a single strand of wire one end of which depends below the plane of the gate frame and is 10 equipped with a weight to normally hold the gate in a vertical position.

In testimony whereof I affix my seal.

JOSEPH R. WALLACE.
